UNITED STATES PATENT OFFICE.

CHARLES SANGSTER, OF BOURNBROOK, ENGLAND, ASSIGNOR TO FRANK A. WILMOT, OF BRIDGEPORT, CONNECTICUT.

LOCK FOR CYCLES.

SPECIFICATION forming part of Letters Patent No. 608,080, dated July 26, 1898.

Application filed December 20, 1897. Serial No. 662,651. (No model.) Patented in England January 13, 1893, No. 789, and November 2, 1894, No. 21,076.

To all whom it may concern:

Be it known that I, CHARLES SANGSTER, director, a subject of the Queen of Great Britain, residing at Cycle Components Manufacturing Company's Works, Bournbrook, near the city of Birmingham, England, have invented certain new and useful Improvements in Locks for Cycles, of which the following is a specification, and for which two several Letters Patent of Great Britain have been granted, dated, respectively, the 13th day of January, 1893, No. 789, and the 2d day of November, 1894, No. 21,076.

This invention relates to an improved locking attachment for cycles, and has for its object a device which admits of being used as a simple bolt or fastening or as a secret combination-lock for preventing the unauthorized use of the machine.

Figure 1 of the accompanying drawings represents a side elevation of a part of the steering-head of a safety-bicycle, in which the steering-pillar admits of being fastened or locked to the sleeve of the ball-head by a lock constructed according to my invention. Fig. 2 represents, upon an enlarged scale, a vertical section of the said lock, showing the bolt of the same withdrawn. Fig. 3 is a like section as Fig. 2, but showing the bolt in its intermediate position—that is, the bolt is in action as a fastening, but is not locked by the cylinders. Fig. 4 is another section of the lock when the bolt is fully shot and locked by arranging the combination of the cylinders. Fig. 5 is a vertical section of Fig. 2 upon the dotted line α , showing the clearances in the cylinders through which the bits on the bolt pass in line with one another. Fig. 6 is an elevation of the bolt separately, while Fig. 7 represents a section, and Fig. 8 a top side plan, of one of the cylinders or washers separately.

The same letters of reference indicate corresponding parts in the several figures of the drawings.

a is the outer sleeve of the steering-head, having a junction-socket a' at its upper end, and b is the stem of the handle-bars, secured to the steering-pillar by the head-clip b' .

Upon the said socket a' are formed two lugs

a^2 , and upon the clip b' is formed a third and corresponding lug b^2 , and these several lugs a^2 b^2 are bored at a^3 b^3 to receive a bolt or key c , which is mounted so as to be capable of vertical movement within the holes a^3 of 55 the lugs a^2 in such a manner that in one position the upper end thereof engages the bolt-socket b^3 in the lug b^2 of the head-clip, and thereby locks the steering-pillar rigidly to the frame. Upon this bolt, which is formed 60 on one side with several bits or projections c' , disposed in a line with one another, are mounted a corresponding number of apertured cylinders or washers d , each of which is formed with a keyway or slot d' , corresponding with 65 the bits or projections c' of the bolt and is recessed at the ends into chambers d^2 , which receive the said projections and permit the cylinders or washers to be moved around both when the bolt is shot or when withdrawn. 70 The washers are milled on their peripheries to facilitate their rotation, and they are also correspondingly marked with circles of figures or letters, so that when the bolt is raised so as to engage its upper end with the aperture b^3 in the lug b^2 of the clip b' the said cylinders may be turned around until their slots or keyways d' are out of alignment with the bits c' of the bolt, which cannot now be withdrawn. The steering-lock is thereby securely 75 locked against rotation.

A flat spring d^3 , surrounding the bolt, is interposed between the top of the uppermost washer and the under side of the lug to prevent the parts rattling.

The figures or letters upon the cylinders d are arranged after the manner of a permutation combination-lock, so that when a prearranged series of numbers or letters are brought into vertical line the keyways also are all in alignment, thus admitting of the bolt being shot or withdrawn and the steering-pillar being locked or unlocked, and after locking the steering-pillar the washers or cylinders are turned into various irregular positions, so 90 that a person ignorant of the prearranged word or sign would find it difficult or impossible to form the required combination of figures or letters to unlock the device.

The recesses or chambers d^2 of the cylin- 100

ders are of such a depth as to admit of the bolt having a certain amount of vertical movement before coming against the center dia-
 phragms d^6 . This allows of the bolt being
 5 projected beyond the face of the top lug a^2
 10 and to engage with the lug b^2 , thus fastening
 the machine, but without locking the bolt by
 the combination. The bolt is retained in this
 15 position (see Fig. 3) by forming a recess a^5 in
 the top lug a^2 , so that the uppermost stud c^3
 20 on the bolt may (by a partial turn being given
 to the bolt) take and ride therein, so that the
 steering of the machine is thus fastened, but
 admits of being readily freed without having
 25 to first go to the trouble of making the com-
 bination of the cylinders. If, however, it is
 desired to bring the permutation locking into
 effect, the cylinders d are set to give the pre-
 arranged combination, when the bolt can be
 30 forced fully home into the position repre-
 sented in Fig. 4, and is prevented from rotat-
 ing by the stud c^3 , taking into the pocket a^6 ,
 and by now disarranging the previous setting
 35 of the cylinders the bolt is permanently locked
 in place until it is desired to unlock it, which
 can only be effected by again setting the cyl-
 inders to the prearranged combination, when
 the gaps or keyways become lineable and
 40 form a passage along which the bits of the
 bolt may pass when automatically withdrawn
 by the spring e .

Although I have hereinbefore shown and
 described the locking bolt or key c as being
 carried by the ball-head sleeve and the aper-
 35 ture b^3 to receive it as being formed in the lug
 b^2 of the handle-bar stem-clip, yet I would
 have it understood that this arrangement of
 parts may, if desired, be reversed—that is,
 the lugs a^2 may be formed upon the handle-
 40 bar stem-clip and carry the bolt, while the
 lug b^2 might be carried on the fixed ball-head
 sleeve.

Having fully described my invention, what

I desire to claim and secure by Letters Patent is—

1. In locking mechanism for cycles, the
 combination of a bolt longitudinally movable
 in bearings carried by one of the parts to be
 locked, and provided with a series of projec-
 tions, a socket to receive said bolt carried by
 50 the other part to be locked, a series of cylinders
 mounted on said bolt and provided with
 slots corresponding with the projections on
 the bolt, and a recess provided in one of said
 55 bearings with which one of the projections of
 the bolt is adapted to engage and in which it
 may be turned to lock the parts together
 without manipulation of the cylinders, sub-
 stantially as described.

2. In locking mechanism for cycles, the
 combination of bearings carried by one of the
 parts to be locked, one of said bearings pro-
 vided with a recess and a pocket, a bolt
 mounted and longitudinally movable in said
 60 bearings and provided with a series of pro-
 jections, a socket carried by the other part to
 be locked, a series of cylinders mounted upon
 said bolt each of which is provided with a
 slotted diaphragm having chambers on each
 65 side of said diaphragm, whereby one of the
 projections carried by the bolt may engage
 the recess in said bearing and be turned
 therein to fasten the parts together without
 manipulating the cylinders, and whereby said
 70 projection on the bolt may enter the pocket
 in said bearing and be confined from rotation,
 when the parts are to be locked by manipu-
 lation of said cylinders, substantially as de-
 scribed.

In testimony whereof I have hereunto set
 my hand in presence of two subscribing wit-
 nesses.

CHARLES SANGSTER.
